United States Patent Office.

MILTON ECKLEY, OF OLNEY, ILLINOIS.

Letters Patent No. 77,468; dated May 5, 1868.

IMPROVEMENT IN MACHINE FOR CLEANING GRAIN.

The Schedule referred to in these Letters Patent and making part of the same.

TO ALL WHOM IT MAY CONCERN:

Be it known that I, MILTON ECKLEY, of the town of Olney, in the county of Richland, and State of Illinois, have invented a new and improved Machine for Cleaning Grain; and I do hereby declare that the following is a full, clear, and exact description thereof, which will enable others skilled in the art to make and use the same, reference being had to the accompanying drawings, forming part of this specification, and in which—

Figure 1 is a longitudinal sectional elevation in the plane of the line x x , fig. 2, and partly broken away to show the riddle.

Figure 2 is a side elevation, partly in section.

Similar letters of reference indicate corresponding parts in the drawings.

This invention relates to an improved machine for cleaning grain, and it consists in the construction of the cylindrical screen, surrounded by wire gauze or netting of different degrees of fineness, one half of their covering forming a chess-screen and the other a cockle-screen, said cylinder containing a spiral flange surrounding the shaft; and in the arrangement of the riddle-fans and cylindrical screen, as will be hereinafter more fully described.

In the drawings, A represents the frame of the machine, composed of four or more uprights, secured together in the ordinary manner, by horizontal pieces framed into them. B is the shaft, having its bearings in the lower cross-bars of the frame. To one end is attached the crank by which the machine is operated. Upon this shaft is mounted the cylindrical screen, D, one end of which is provided, near its periphery, with a discharge-opening, a , shown in dotted lines fig. 2, and the other provided with a central opening, through which the spout passes to conduct the grain into said cylinder. The periphery of the cylinder is composed, one half of fine wire netting or gauze, having square openings forming the cockle-screen d , and the other of coarser wire netting or gauze, having rectangular openings, forming the chess-screen d' , both of which are secured to the periphery of the ends of cylinder by any suitable means.

The length of the screen D, I prefer to make equal to its diameter, although this is not absolutely essential. Around the shaft, and within the cylinder, a metallic flange, E, is placed, for separating the parcels of grain as they enter the cylindrical screen.

As the screen is rotated, the grain is carried round, by the spiral flange E, over a space about six times as large as the number of spiral turns in the cylinder. For example, the number of spiral flanges being four in a screen, of two feet in length and diameter, the grain, passing four times around the cylinder, passes over a space of twenty-four feet before it is discharged through the opening a at the end.

By means of the screens d and d' , the cockle and chess are entirely separated from the sound grain, and fall to the bottom of the machine.

Upon the upper portion of the framing, and having its bearings therein, a shaft, F, is placed, parallel with the shaft B, and nearly in the same vertical plane, carrying near one end the fans G G, which are rotated with the shaft F by means of the belt f passing over the cylinder E and pulley e . The fans are arranged to turn in circular openings g , formed in the top, h , of the frame, and in the side of the frame, and a wide cross-piece, h' , parallel with the side of the frame. This cross-piece is slightly cut away upon its lower edge to fit over the cylinder D. By closing the top and side around the periphery of the fans, the air is drawn through the latter by their revolutions, and a stronger draught created.

The hopper H is placed upon the top of the framing opposite the fans, and beneath it the riddle K is suspended by means of the rods i . A shaking-motion is imparted to it by suitable means from the shaft F. In the drawings, a crank-connection is shown for this purpose. Beneath the riddle, the inclined spout I is placed, connecting with the spout J, which conducts the grain to the interior of the cylindrical screen D.

The operation is as follows: The grain is poured into the hopper, and is discharged upon the riddle, the shaking of which separates the grain from all coarser matters. At the same time the dust and lighter particles are blown out through the side of the frame at K by the fans. The grain thus cleaned falls through the riddle,

and is conducted by the spouts I J to the interior of the cylindrical screen, where the cockle and chaff are removed by the screens d d', and the sound grain carried along by the spiral flange E, and discharged, thoroughly cleaned, through the opening a in the outer end of the cylinder.

By this arrangement the grain is entirely freed from foreign substances in a very expeditious and thorough manner.

Having thus described my invention, what I claim as new therein, and desire to secure by Letters Patent, is—

1. The arrangement of the fans G, riddle K, and compound cylindrical screen D, substantially as described for the purpose specified.

2. The construction and arrangement of the fans G, riddle K, spouts I J, compound cylindrical screen D, and shafts B F, substantially as described for the purpose specified.

MILTON ECKLEY.
